UNITED STATES PATENT OFFICE.

MORTON HAVENS, JR., OF ALBANY, NEW YORK.

DESIGN FOR A BRANCH BOX FOR INSULATED ELECTRIC WIRES.

No. 39,767.

Specification for Design.

Patented Jan. 12, 1909.

Application filed February 16, 1906. Serial No. 301,514. Term of patent 7 years.

To all whom it may concern:

Be it known that I, MORTON HAVENS, Jr., a citizen of the United States, residing and having my post-office address at No. 79 Chapel street, in the city of Albany, county of Albany, and State of New York, have invented a new, original, and ornamental Design for a Branch Box for Insulated Electric Wires.

In the accompanying drawing, Figure 1 is a perspective view of a branch box for insulated electric wires, embodying my design, and Fig. 2 is a perspective view of said branch box shown as inverted.

This design for branch boxes comprises

an elongated body having a closure on one side constituting a continuation of the lines of the body and having nipples projecting from each end of the body. The bottom of the body is curved and all parts of the device are joined by gradual curves so as to produce an ornamental effect.

What I claim is:—

The ornamental design for a branch box for insulated electric wires, substantially as herein shown and described.

MORTON HAVENS, JR.
